UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,256,991.

Specification of Letters Patent. Patented Feb. 19, 1918.

Application filed October 16, 1916. Serial No. 125,892.

To all whom it may concern:

Be it known that I, FRANK DUTCHER, a citizen of the United States, residing at Versailles, in the county of Allegheny and State of Pennsylvania, have invented certain new and useful Improvements in Railway Signal-Torpedoes, of which the following is a specification, reference being had therein to the accompanying drawing.

This invention relates to improvements in railway signal torpedoes, and pertains to a paper case torpedo, and the object of the invention is to provide a clamping ring or member which is destroyed by the flame and heat of the explosion, thus providing a clamping member which will not fly and injure by-standers, the whole structure therefore making a torpedo which is non-flying and harmless.

The type of torpedo to which the invention is here shown as applied is of the "button top" or "bull's eye," though the clamping member is capable of being used for closing the case of any type of non-flying or paper torpedo.

The present invention also involves the idea of applying a fire-proofing coating to the exterior of the clamping ring or member, whereby it is not readily susceptible to ignition and destruction from the outside.

In the accompanying drawings—

Figure 1 is a perspective view of a torpedo involving my invention.

Fig. 2 is a vertical sectional view of Fig. 1.

Fig. 3 is an enlarged sectional view of a portion of the torpedo, showing in detail the clamping action of the clamping ring or member.

Fig. 4 is a perspective view of the several parts composing the torpedo, the parts shown in separated relation.

Fig. 5 is a sectional view showing the manner of attaching a spring rail-engaging strap to the torpedo.

Fig. 6 is a bottom plan view of Fig. 5.

Fig. 7 is an enlarged perspective view of the clamping ring or member, the same being shown partly in section.

The type of torpedo here shown to which the new clamping member is applied is composed of a bulged or button top 1, a plastic explosive 2, a bottom disk 3 and a rail-strap carrying disk 4. The top 1 is provided with a projecting flange 5, and the disks 3 and 4 are made of a size correspond-

ing to the size of the top 1, including its flange 5. The explosive tablet 2 and the disks 3 and 4 are placed in the relation shown in Figs. 2 and 3, ready to receive the clamping member 6. This clamping member 6 is first in the shape shown in Fig. 4, which is L-shaped in cross-section, having a bottom flange 7 and a flange 8, which is turned over on top of the flange 5 and clamped down thereon.

The improvement herein involved is making the clamping member 6 of celluloid or equivalent material, which is readily inflammable and readily destructible by flame and heat. It is shaped as shown in Fig. 4 and will be pressed down to the clamping shape shown in Figs. 1, 2, 3 and 7, by warm dies (not shown) since the material is readily pliable under the action of gentle heat, and will remain in the pressed shape after it is cooled. In this instance, the flange 5 and the disks 3 and 4 may be connected by waterproof cement and the member 6 will serve to hold the disks and the flange against separation. In fact, by making the clamping ring 6 of sufficient thickness, it can be made to fit and clamp the flanged and under disk sufficiently tight to prevent the entrance of water or moisture under the clamping member, and thus making a waterproof joint between the parts of the paper case.

When the torpedo explodes and the explosive breaks out at any point where the clamping ring 6 is located, the flame and heat of the explosion will practically instantly destroy the clamping ring where it breaks out whereby there are no flying particles of the released portion of the clamping ring to injure persons who may happen to be standing by.

Where metal clamping members are provided, sometimes the explosive breaks out where the metal clamping member is located and tears away a part of the metal clamp and hurls it through the air with liability to injure persons. While this tearing away of the metal clamp does not occur frequently, it does occur at times with the resultant danger therefrom. By using a clamping member made of a material which is readily destroyed by flame and heat, this danger is avoided and an absolutely harmless and non-flying torpedo is the result.

The rail-engaging strap 10 may be applied to the torpedo in any desired manner,

without affecting the present invention. As shown in Figs. 1 and 2, the rail-engaging strap 10 is attached by passing it through openings 11, made in the outer disk 4.

- 5 When, however, a spring rail-engaging strap 12 is to be used, then a suitable clip 13 will be used, and this clip may be of any desired material, so that it would be destroyed by the flame and heat of the explosive.
- 10 However, metal may be used and the advantages of the invention still remain, because the explosive force, if it should break out at the edge of the torpedo, will break out at the points of least resistance, so that the edge 15 of the torpedo not reinforced by the metal clip 13 would be the part to break out under the force of the explosive and the celluloid clamping ring would be destroyed, as above stated, by the flame and heat of the 20 explosive that hit it at any point.

For the purpose of preventing the clamping ring or member 6 from being readily ignited from the outside in the completed torpedo, it is provided with a fire-proof 25 coating 14, of any suitable material for that purpose, such, for instance, as sodium silicate, though other fire-proof coating may be used.

Having thus described my invention, what 30 I claim and desire to secure by Letters Patent is:-

1. A non-flying railway signal torpedo, comprising a fiber case composed of a plurality of parts, an explosive between them, 35 and a member clamping the parts together composed of material readily destructible by flame and heat and compressible to maintain clamping position in the presence of heat.
- 40 2. A non-flying railway signal torpedo, comprising a plural-part fiber case, an explosive between them, and a non-fibrous inflammable clamping member for the parts of the case.
- 45 3. A non-flying torpedo comprising a fiber

case and a clamping member composed of material readily destroyed by flame and heat, the clamping member having a fire-proof external coating.

4. A non-flying torpedo comprising a fiber 50 case, a celluloid closing member therefor, the closing member having an external coating of sodium silicate, for the purpose described.

5. A non-flying railway signal torpedo, 55 comprising a paper or fiber case composed of separate upper and lower members, an explosive between them, the members projecting beyond the explosive to form flanges, and a ring-like clamping member U-shaped 60 in cross-section and embracing and clamping the parts of the case together.

6. A non-flying railway signal torpedo, comprising a plural-part fiber case, an explosive between them, and a ring-like clamping member, 65 the clamping member U-shaped in cross-section and embracing the edges of the parts of the case and composed of material readily destructible by flame and heat.

7. A non-flying torpedo, comprising a 70 fiber case, and a ring-like closing member for the case and composed of material readily destroyed by flame and heat and said ring-like closing member having a fire-proof external coating.

8. A non-flying railway signal torpedo, comprising a plural-part fiber case with peripheral projecting flanges, and a ring-like clamping member U-shaped in cross-section 80 and embracing the said flanges of the cases and composed of inflammable material compressible to maintain U-shaped clamping position in the presence of heat.

In testimony whereof I hereunto affix my signature in the presence of two witnesses. 85

FRANK DUTCHER.
